UNITED STATES PATENT OFFICE.

ROBERT O. HAGERMAN, OF BUTTE, MONTANA.

HOLLOW PARTITION.

1,073,041.

Specification of Letters Patent.

Patented Sept. 9, 1913.

Application filed December 3, 1912. Serial No. 734,746.

To all whom it may concern:

Be it known that I, ROBERT O. HAGERMAN, a citizen of the United States, residing at Butte, in the county of Silverbow 5 and State of Montana, have invented new and useful Improvements in Hollow Partitions, of which the following is a specification.

This invention has relation to fire-proof 10 structures, the object being the provision of a wall, partition or like part embodying novel supports and a peculiar arrangement of connecting pieces for supporting the metal lathing or like base designed to receive the plaster or analogous composition.

The invention contemplates a metal support formed of a metal strip of suitable gage and width having its edge portions recurved to form stiffening and strengthening 20 flanges, said strip having portions intermediate of its longitudinal edges cutaway to provide spaces to receive the longitudinal strips or runners by means of which the supports are connected and the partition, 25 wall or like part strengthened and reinforced.

The invention consists of the novel features, details of construction and combination of parts, which hereinafter will be 30 more particularly set forth, illustrated in the accompanying drawings, and pointed out in the appended claim.

Referring to the drawings, forming a part of the specification, Figure 1 is a perspective view of a wall embodying the invention, parts being broken away. Fig. 2 is a perspective view of one of the supports or metal studs, showing the same on a larger scale. Fig. 3 is a horizontal section. Fig. 40 4 is a vertical section of a part of the partition.

Corresponding and like parts are referred to in the following description, and indicated in all the views of the drawings, by 45 the same reference characters.

The essential feature of the invention is a metal support or stud which may be of any length and size depending upon the specific use and strength required. The 50 support or stud is constructed of a strip of sheet metal of suitable width and gage having its edge portions recurved to form stiffening and strengthening flanges. The edges of the recurved portions stand apart 55 to form a space 1. In the preferable construction edge portions of the metal strip

are bent laterally in the same direction at a right angle, as indicated at 2, and are rebent, as at 3, forming flanges which extend parallel with the main portion of the strip. 60 Intermediate portions are cut from the strip to form spaces 4 which lighten the support or stud and at the same time provide openings for the connecting and bracing strips which extend at a right angle to the 65 studs or supports. The intermediate portions 5 between the spaces 4 are utilized as supports for the connecting and bracing strips as well as serving as ties between the edge portions of the studs or supports. 70 The support may embody any number of spaces 4 or connecting pieces 5 and the length of the spaces 4 may vary. The width of the spaces 4 corresponds approximately to the space 1 between the inner 75 flanges 3 so that the longitudinal strips may have a free passage. The studs or supports may be secured at their ends to the structure in any manner. Clips 6 may be employed for attaching the ends of the 80 studs to the support.

The connecting and bracing strips may be metal, as indicated at 8, or may consist of wood, as shown at 9 and 10. The wooden strips 9 are located near the ceiling or upper ends of the studs and are adapted to have picture molding or other interior finishing strips nailed thereto. The lower strip 10 forms convenient means for nailing the sub-base or washboard to the partition or wall. The intermediate strips 8 are of metal and in conjunction with the strips 9 and 10 serve to stiffen and brace the partition or wall as a whole. The several strips, which may be designated as runners or braces, may be attached to the studs in any manner, usually by means of wire which is twisted about the parts in a manner well understood in the art. The metal lathing 11 may be wired or otherwise secured to opposite edges of the studs or supports and is intended to receive the plaster or other finishing coat. The space between the plaster may be utilized for ventilation and also to receive electric and other conduits, wires 105 or the like.

From the foregoing description, taken in connection with the accompanying drawings, the advantages of the construction and of the method of operation will be readily apparent to those skilled in the art to which the invention appertains, and while

I have described the principle of operation of the invention, together with the device which I now consider to be the best embodiment thereof, I desire to have it understood that the device shown is merely illustrative, and that such changes may be made when desired as are within the scope of the claim appended hereto.

Having thus described the invention what is claimed as new, is:—

A partition of the character specified comprising studs each consisting of a metal strip having its edge portions bent in the same direction at a right angle and having edge portions of the bent parts rebent and facing inwardly, the body portion of the

stud having oblong openings in its length of a width equal to the distance between the rebent edge portions of the metal strip, and connecting and bracing strips extending through the oblong openings of the studs and of a width to have their edge portions touch the edges of the strips bordering upon the oblong openings and the edges of the rebent edge portions of such strips.

In testimony whereof I affix my signature in presence of two witnesses.

ROBERT O. HAGERMAN.
